AUTOMATIC TEMPLATE FOLLOWING
PROFILING TRACER

Robert D. Shaw, Hartford, Conn., assignor to
Pratt & Whitney Company, Hartford, Conn., a
corporation of New Jersey

Application October 18, 1934, Serial No. 748,903

6 Claims. (Cl. 90—62)

This invention relates to profiling machines, particularly to an automatic profiling machine controlled and operated by electrical means. More particularly the invention relates to a template following tracer for a machine such as disclosed in U. S. Patent No. 1,683,581 granted September 4, 1928.

A primary object of the present invention is to improve the construction of the template following tracer mechanism enabling the machine to automatically follow and cut the profile of a generally circular or curved outline.

The present invention constitutes an improvement upon the tracer and associated mechanism shown and described in my copending application Serial No. 717,760 filed March 28, 1934, entitled Profiling tracer.

A feature of importance in the present improved construction is the provision of resilient retaining means for the tracer lever, the resultant force of which may be angularly varied during operation of the machine and while the tracer is following the template being reproduced.

Another feature of importance is that angularly disposed resilient means, preferably in the form of angularly spaced tension springs, are employed to normally hold the tracer lever toward the edge of the template being followed, the tension of one of these springs being adjustable during operation of the machine, cams being employed for that purpose to vary the position of the outer end of the spring.

With the above and other objects in view my invention includes the features of construction and operation set forth in the following specification and illustrated in the accompanying drawing.

In the accompanying drawing annexed hereto and forming a part of this specification, I have shown my invention embodied in an automatic profiling machine of the type indicated in the above referred to patent and application, but it will be understood that the invention can be otherwise embodied and that the drawing is not to be construed as defining or limiting the scope of the invention, the claims appended to this specification being relied upon for that purpose.

50 In the drawing:

Figure 1 is a longitudinal sectional view of the tracer lever, its housing and parts cooperating therewith.

Fig. 2 is an end elevation taken from the left hand end of Fig. 1.

Fig. 3 is an end elevation taken from the right end of Fig. 1 upon the broken line 3—3, and

Fig. 4 is an end elevation of the template and contacting end of the tracer lever shown in several different operative positions.

In the above mentioned drawing I have shown but one embodiment of the invention which is now deemed preferable, but it is to be understood that changes and modifications may be made within the scope of the appended claims without departing from the spirit of the invention.

Briefly and in its preferred aspect my invention may include the following principal parts: First, a tracer lever mounted for universal oscillation about an intermediate point longitudinally thereof and having a template following member and contact making and breaking means at opposite ends thereon; second, a member mounted for rotation substantially upon the central line of the tracer lever and having interconnecting means with the template so that this member is forced to rotate as the template is traversed by the tracer; third, a rotatable member adjacent the end of the tracer lever opposite the template and driven in timed relation with the first mentioned rotatable member; fourth, resilient means coupling the second rotatable member and the tracer lever for normally holding the tracer in contact with the template; fifth, a supplemental resilient means disposed at an angle to the first resilient means connecting the second rotatable member and the tracer lever and tending to force the tracer along the outline of the template; sixth, a pivotal arm to which the last mentioned resilient means is attached at its outer end so that oscillation of this arm will increase or decrease the tension of the auxiliary resilient member; and seventh, cams fixed in position for engagement by the extended end of the pivotal arm so that the tension of the auxiliary resilient member may be controlled in different portions of the outline being followed as the tracer engages different portions of the template.

In the use of the template following tracer disclosed in my copending application it has been found that the forms of outlines satisfactorily followed are limited. Outlines departing to extreme degrees from a circle could not be followed satisfactorily with each of the resilient means or tension springs retained in one adjusted position. At certain parts of the outline the position of the auxiliary or advancing spring should be changed or its tension varied. This is for the purpose of varying the advancing force or tendency of the tracer to advance along the tem-

plate. The direction of the resultant force of the two angularly disposed springs acting upon the tracer lever must be adjustable to a limited extent, this being accomplished by varying the tension of one of the springs by means presently to be disclosed. In the present instance the adjustment is effected upon the auxiliary spring only. By increasing the tension of this spring the tendency for or ability of the tracer to advance along the outline of the template is increased.

Referring more in detail to the figures of the drawing, I provide a tracer support 10 and tracer lever 11 similar generally to those shown and described in Patent No. 1,683,581, this lever 11 being mounted for oscillation about an intermediate point as by means of the ball and socket bearing 12. At one end of this tracer lever 11 is a template engaging member 13, this end having a disc thereon the diameter of which is chosen to correspond to that of the cutter being used. Adjacent the opposite or rear end of the tracer lever 11 are the four pairs of contact making and breaking members 14 similar in every way to those shown in Patent No. 1,840,853. At the extreme rear end of the tracer lever 11 opposite the template contacting end there is provided a mounting or bearing for a rotatable member 15 in the form of a ring or disc to which are attached the outer ends of tension springs 16 and 17. The inner ends of these springs 16 and 17 are attached in any suitable manner to the extreme end of the lever 11. These springs 16 and 17 are shown more clearly in Fig. 2 and it will be noticed that they are attached in fixed positions angularly spaced apart to the ring 15 to radially mounted screws 18 and 19 respectively. By adjustment of these screws 18 and 19 toward or from the axis of the tracer lever 11 by means of their nuts the tension of the springs 16 and 17 and the resilient force urging the tracer lever toward the template may be widely varied. These springs 16 and 17 act upon the tracer lever 11 in the same manner as the springs disposed at the template contacting end of the tracer in my copending application.

As shown in Fig. 2 one of the springs, namely spring 16, has its outer end attached to its screw 18 which is threaded into a bracket 20 secured rigidly to the ring 15. The other spring 17, however, is attached by its screw 19 to a pivotally mounted lever 21 which may oscillate to increase and decrease the tension of this spring. The lever 21 may preferably be mounted in a bracket 22 fixed to the ring 15. The function of this means to obtain varying tensions in the spring will presently be described.

In order to vary the tension of this spring 17 during operation of the machine on which it is mounted, cam plates 24 are provided on a fixed member 25 surrounding the ring 15, their inner edges being adapted to engage the extended opposite end of the spring holding lever 21. By forming the inner edges of the plates 24 of any contour so that the lever 21 is moved to different oscillated positions the tension of spring 17 may be controlled throughout the operation and while the tracer 13 traverses the entire periphery of the template M. In the present instance the template M is of ellipsoidal form and the tension of spring 17 is varied in alternate quadrants as the tracer proceeds about the template. The cams 24 therefore take the form of arcuate segments of approximately 90° each. In alternate quadrants, therefore, the lever 21 may bear upon

the inner periphery of the fixed supporting member 25 and be held in one oscillated position and in the other portions may be engaged by edges of the cams 24 and held in an oscillated position which materially increases the tension of the spring 17.

In order to rotate this ring or disc 15 on which the springs 16 and 17 are mounted and therefore rotate the springs to constantly urge the tracer member 13 toward the particular part of the template outline being followed and being cut by the machine, driving means are provided from the front or template following end of the tracer mounting 10. At this end of the tracer mounting 10 is a rotatable member 28 generally similar to the corresponding rotatable member shown in my copending application. This member 28 is provided with a radially disposed slot 29 engaging a projection 30 outstanding centrally from the template M as shown and described in my copending application. This rotatable member 28 is provided with gear teeth on its outer periphery which engage a gear 31 on one end of an intermediate shaft 32 suitably supported and extending parallelly to the tracer mounting 10. The rear end of this shaft 32 is provided with a gear 33 meshing with gear teeth provided on the rotatable member 15 at the opposite end of the tracer lever 11. The gearing is so disposed that movements of the rotatable members 28 and 15 at opposite ends of the tracer lever 11 are always in exactly the same relative angular or rotative position. The springs 16 and 17 are, when in operative position and during operation, disposed substantially on the opposite side of the axis of the tracer 11 as the slot 29. An extension of the slot 29 to the opposite side of the ring 28 would intersect the angle between the two springs 16 and 17 which is indicated in Fig. 2.

What I claim is:

1. A template following tracer for profiling machines comprising in combination, a universally oscillatory tracer lever, oscillation of which controls relative movement between a cutter and work, a member mounted on said lever and rotatable about a fixed axis substantially concentric with said lever, means to rotate said member during operation as the tracer traverses the template, resilient means normally holding said tracer toward said template in all positions of the tracer relative to the template, the direction of action of said resilient means being adjustable at different portions of the path of movement of the tracer about the template.

2. A template following tracer for profiling machines comprising in combination, a universally oscillatory tracer lever, oscillation of which controls relative movement between a cutter and work, a member mounted on said lever and rotatable about a fixed axis, springs mounted on said rotatable member and engaging the tracer lever whereby said tracer lever is held in contact with the template during operation, means to rotate said member as the tracer arm traverses the periphery of the template, and means varying the tension of one of said springs during operation.

3. A template following tracer for profiling machines comprising in combination, a universally oscillatory tracer lever, oscillation of which controls relative movement between a cutter and work, a member mounted on said lever and rotatable about a fixed axis, springs mounted on said rotatable member and engaging the tracer lever whereby said tracer lever is held in contact with the template during operation, means to rotate

said member as the tracer arm traverses the periphery of the template, and a cam adjacent said rotatable member for varying the tension of one of said springs during operation.

- 5 4. A template following tracer for profiling machines comprising in combination, a universally oscillatory tracer lever, oscillation of which controls relative movement between a cutter and work, a member mounted on said lever and rotatable about a fixed axis, angularly spaced springs disposed between said rotatable member and the tracer lever whereby said tracer lever is held in contact with the template during operation, means to rotate said member as the tracer 10 arm traverses the periphery of the template, and cam means operative upon one of said springs to vary its tension at predetermined portions of the path of movement of the tracer about the template.
- 15 5. A template following tracer for profiling machines comprising in combination, a universally oscillatory tracer lever, oscillation of which controls relative movement between a cutter and work, a member mounted on said lever and rotatable about a fixed axis, angularly spaced springs disposed between said rotatable member and the tracer lever whereby said tracer lever is held in contact with the template during operation, means to rotate said member as the tracer 20 arm traverses the periphery of the template, and cam means operative upon one of said springs to vary its tension at predetermined portions of the path of movement of the tracer about the template to vary its tension.
- 25

tatable about a fixed axis, means to rotate said member during operation as the tracer traverses the template and in timed relation therewith, resilient means normally holding said tracer against said template in all positions of the tracer relative to the template, the tension of said resilient means being adjustable at predetermined points in the path of movement of said tracer about said template.

6. A template following tracer for profiling machines comprising in combination, a universally oscillatory tracer lever, oscillation of which controls relative movement between a cutter and work, a member mounted on said lever and rotatable about a fixed axis, means to rotate said member during operation as the tracer traverses the template and in timed relation therewith, and angularly spaced resilient members normally holding said tracer against said template in all positions of the tracer relative to the template, 15 one of said resilient means being adjustable at predetermined points of the path of movement of the tracer about the template to vary its tension.
